(57) **CLAIM**

The ornamental design for a headlight for a vehicle, as shown and described.

DESCRIPTION

This application contains subject matter related to the following co-pending U.S. design patent applications:

Application Ser. No. 29/482,593, filed Feb. 20, 2014 and entitled "Vehicle, Toy, and/or Replicas Thereof;"

Application Ser. No. 29/482,594, filed Feb. 20, 2014 and entitled "Front Portion of a Vehicle, Toy, and/or Replicas Thereof;"

Application Ser. No. 29/482,596, filed Feb. 20, 2014 and entitled "Vehicle, Toy, and/or Replicas Thereof;" and

Application Ser. No. 29/482,597, filed Feb. 20, 2014 and entitled "Front Portion of a Vehicle, Toy, and/or Replicas Thereof."

FIG. 1 is a right perspective view of a first embodiment of a headlight for a vehicle according to the design;

FIG. 2 is a front view thereof;

FIG. 3 is a right side view thereof; and

FIG. 4 is a top view thereof.

FIG. 5 is a left perspective view of a second embodiment of the headlight for a vehicle according to the design;

FIG. 6 is a front view thereof;

FIG. 7 is a left side view thereof; and

FIG. 8 is a top view thereof.

FIG. 9 is a right perspective view of a third embodiment of the headlight for a vehicle according to the design;

FIG. 10 is a front view thereof;

FIG. 11 is a right side view thereof; and

FIG. 12 is a top view thereof.

FIG. 13 is a left perspective view of a fourth embodiment of the headlight for a vehicle according to the design;

FIG. 14 is a front view thereof;

FIG. 15 is a left side view thereof; and,

FIG. 16 is a top view thereof.

The broken lines in the drawings illustrate portions of a headlight for a vehicle which form no part of the claimed design.
